UNITED STATES PATENT OFFICE.

NORBERT L. OBRECHT AND FRANK E. PRICE, OF PONTIAC, MICHIGAN.

DESIGN FOR AN AUTOMOBILE BUMPER.

Application filed January 30, 1925. Serial No. 12,206. Term of patent 3½ years.

To all whom it may concern:

Be it known that we, NORBERT L. OBRECHT and FRANK E. PRICE, citizens of the United States, residing at Pontiac, in the county of Oakland, State of Michigan, have invented a new, original, and ornamental Design for Automobile Bumpers, of which the following is a specification, reference being had to the accompanying drawing, which forms a part of this specification.

The figure is a perspective view of an automobile bumper, showing our new design.

We claim:—

An ornamental design for an automobile bumper as shown.

In testimony whereof, we sign this specification.

FRANK E. PRICE.
NORBERT L. OBRECHT.
